UNITED STATES PATENT OFFICE.

HARRY S. HART, OF CHICAGO, ILLINOIS.

HOPPER-CAR ARRANGEMENT.

Application filed August 4, 1921. Serial No. 489,698.

To all whom it may concern:

Be it known that I, HARRY S. HART, a citizen of the United States, residing at Chicago, in the county of Cook and State of Illinois, have invented certain new and useful Improvements in Hopper-Car Arrangements, of which the following is a specification.

This invention relates to a new and improved hopper car arrangement, and more particularly to an arrangement of dump doors for such cars.

In connection with a number of hopper car uses, it is highly desirable to provide dumping doors adapted selectively to dump the material between the rails or to either side of the rails, and to avoid flooding the rails.

It is an object of the present invention to provide a door arrangement for such cars adapted selectively to dump between or beside the rails. It is a further object to provide a construction of this character which is simple in design and composed of but few and rugged parts. It is an additional object to provide the doors so associated with the car body as to give a maximum of carrying capacity.

Other and further objects will appear as the description proceeds.

In the embodiment of my invention selected for illustration, I have shown a car having the usual underframe composed of center sills and cross sills, the car being provided between the trucks with a longitudinal hopper having its apex beneath the center sill.

As my invention relates particularly to this hopper arrangement, I have not illustrated or described the construction of the car at the ends over the trucks. It will be understood, however, that this may be the well known construction of the Hart convertible car.

I have illustrated a preferred embodiment of my invention in the accompanying drawings in which—

Figure 1 is a transverse section of a hopper car provided with the door construction of the present invention, the doors being closed.

Figure 2 is a fragmentary view similar to Figure 1 and showing the center dump doors open.

Figure 3 is a view similar to Figure 2 showing the right lateral dump door open,

Referring to the drawings, the car comprises the end 4, the sides 5, center sills 6, and cross frames 7. The lower portions 8 of the cross frames are formed in the shape of a downwardly directed V. At either side the car is provided with inwardly and downwardly sloping fixed floor sections 9. The longitudinally extending frame members 10 are secured intermediate the legs of the V- portions 8, these members 10 as shown being of I-beam cross section. The outwardly opening doors 11 are pivoted at 12 against the outer face of the members 10. The doors 11 are connected by chains 13 to operating shafts 14, which shafts may be rotated by any desired mechanism (not shown). The inwardly opening center dump doors 15 are pivoted at 16 adjacent the inner face of the members 10. The doors 15 upon opposite sides of the car meet at 17, at the apex of the V-member 8. The center door operating shaft 18 is carried by the members 8 above the apex of the V and below the center sills 6. This shaft 18 carries the gear wheel 19, which is in mesh with the worm gear 20 upon the laterally extending shaft 21, this shaft being provided with operating hand wheels 22. As best shown in Figure 2, the shaft 18 is also provided with the operating arms 23 and 24, these arms being separated by an angle of approximately ninety degrees. The arm 23 is connected by link 25 to the right hand door 15. The arm 24 is similarly connected by a link 26 to the left hand door 15. The links 26, as shown, are arcuate in contour in order that they may partially encircle the shaft 18 when the center doors are closed, as shown in Figures 1 and 3.

In the operation of my dump door arrangement the center doors for dumping between the rails are operated by rotating the shaft 21 by means of the hand wheels 22, this rotation being transmitted to the shaft 18 by the worm gear 20 and gear wheel 19. The arms 23 and 24 and links 25 and 26 are thus rotated from the position of Figure 1 to that of Figure 2. Material in the car then passes by gravity out through the two doors 15, these doors serving to direct it between the rails. The side doors 11 are held in their closed position and serve to aid in guiding the material to the center opening. The car will cleanly dump and all material will completely pass out. For lateral dumping to either side, the

corresponding shaft 14 is rotated to unwind the chain 13 and thus to permit the door 11 to swing downwardly, as shown, at the right of Figure 3. The door is of sufficient size so that it extends beyond the rail when in its fully opened position, and the material is thus prevented from piling up on the rail. The inner edge of the door opening is sufficiently close to the lower part of the material carrying hopper so that the greater part of the material is guided through the opening by the fixed sides and by the doors upon the opposite side of the car. To close the door the shaft 14 is rotated in the reverse direction.

It will be seen that my construction, as shown and described, provides a hopper car carrying a maximum amount of load and in which the door construction is simple and rugged and may be readily operated, to deposit the material either between the rails or outside the rails and without flooding them.

What I claim is:

1. In a dump car, a bottom comprising inwardly sloping side portions, each said side portion comprising outwardly opening doors for side dumping and inwardly opening doors for center dumping, and means for operating said doors.

2. In a dump car, a bottom comprising inwardly sloping side portions, each said side portion comprising outwardly opening doors for side dumping and inwardly opening doors for center dumping, said outwardly and inwardly opening doors being independent of each other when closed, forming, together, continuous inwardly sloping side surfaces.

3. In a dump car, a bottom comprising inwardly sloping side portions, each said side portion comprising outwardly opening doors for side dumping and inwardly opening doors for center dumping, said outwardly and inwardly opening doors, when closed, forming, together, continuous inwardly sloping side surfaces, the adjacent edges of said doors being pivotally connected to the car.

4. In a dump car, a bottom comprising inwardly sloping side portions, each said side portion comprising outwardly opening doors for side dumping and inwardly opening doors for center dumping, the outwardly opening doors, when closed, serving to guide material through the inwardly opening doors when the latter are opened.

5. In a dump car, a bottom comprising inwardly sloping side portions, each said side portion comprising outwardly opening doors for side dumping and inwardly opening doors for center dumping, a longitudinally extending shaft adjacent the inwardly opening doors and links connecting said doors to the shaft whereby rotation of the

shaft in one direction closes both doors and in the opposite direction opens both doors, and means for operating the outwardly opening doors.

6. In a dump car, center sills, transverse frames having downwardly extending V-portions, a longitudinally extending frame member secured intermediate each leg of the V, inwardly opening doors for center dumping pivoted adjacent the inner faces of the longitudinal frame members, and outwardly opening doors pivoted adjacent the outer faces of said members, and means for operating said doors.

7. In a dump car, center sills, transverse frames having downwardly extending V-portions, a longitudinally extending frame member secured intermediate each leg of the V, inwardly opening doors for center dumping pivoted adjacent the inner faces of the longitudinal frame members, and outwardly opening doors, pivoted adjacent the outer faces of said members, said outwardly and inwardly opening doors, when closed, forming, together, continuous inwardly sloping side surfaces.

8. In a dump car, center sills, transverse frames having downwardly extending V-portions, a longitudinally extending frame member secured intermediate each leg of the V, inwardly opening doors for center dumping pivoted adjacent the inner surfaces of the longitudinal frame members, and outwardly opening doors, pivoted adjacent the outer faces of said members, the outwardly opening doors, when closed, serving to guide material through the inwardly opening doors when the latter are opened.

9. In a dump car, center sills, transverse frames having downwardly extending V-portions, a longitudinally extending frame member secured intermediate each leg of the V, inwardly opening doors for center dumping pivoted adjacent the inner faces of the longitudinal frame members, and outwardly opening doors pivoted adjacent the outer faces of said members, a longitudinally extending shaft carried by the transverse V-frames adjacent the apex thereof and links connecting the shaft to the inwardly opening doors whereby rotation of the shaft in one direction closes both doors and in the opposite direction opens both doors, and means for operating the outwardly opening doors.

10. A dump car having its floor between the trucks in the form of a longitudinally extending hopper having its apex beneath the center line of the car, the sides of said hopper comprising doors hinged at an intermediate point of the sides to swing downwardly toward each other.

Signed at Chicago, Illinois, this 26th day of July, 1921.

HARRY S. HART.
